RAZOR BLADE HONING DEVICE

Charles Eugene Holtzclaw, Canton, N. C.

Application September 7, 1932. Serial No. 632,040

2 Claims. (Cl. 51—158)

This invention relates to a device for sharpening all types of double-edged safety razor blades of the so-called Gillette type.

I am aware of the fact that various styles and forms of honing stones and concaved glass bodies and the like have been utilized for sharpening the cutting edges of razor blades.

In carrying the present inventive conception into practice, I have evolved and produced a novel and practicable glass base embodying a half-cylinder and constructed to accommodate a pendulous operating lever provided with means to aid in holding the blade firmly in position for effective results.

15 Stated more explicitly, I have discovered a simple and economical structure including a rockably mounted blade holder which systematically and uniformly coacts with the blade in maintaining the blade firmly in abrading contact with the concaved honing surface in order that the blade will be swept back and forth in a definite regular path so that the edges will be refined and reconditioned accurately and uniformly for more favorable shaving results.

20 Frequently in devices of this type the blade is moved by one hand of the operator, sometimes in a circular direction, and other times in a predetermined straight path. Manifestly, however, in the hands of an inexperienced person, the results obtained from this method of sharpening are unsatisfactory indeed.

25 The principal purpose of the present invention is to provide a reliable and carefully perfected structure which will accomplish the desired results in a safe, positive and practicable manner.

30 Other features and advantages will become more readily apparent from the following description and drawings.

In the drawings:

35 Figure 1 is an end elevation of the structure designed in accordance with the principles of the present inventive conception.

Figure 2 is a top plan view thereof.

40 Figure 3 is a perspective view of the actuating holder and lever.

45 Figures 4 and 5 are sections taken on the planes of the lines 4—4 and 5—5, respectively, of Figure 2.

50 Figure 6 is a bottom plan of the retaining element on the lever.

55 Figure 7 is a fragmentary detail section through the lower actuating end of the pendulous lever.

Referring now to the drawings by distinguishing reference characters, it will be observed that

the numeral 8 designates a part which may be broadly referred to as a base. This is all glass and of appropriate dimensions and embodies a pair of spaced parallel end walls 9 whose lower end portions are fashioned as indicated at 10 in Figure 5 to provide feet to rest on a table or support.

55 Formed between the end walls is the hone 11, this being of semi-cylindrical form in cross sectional shape. Attached to the intermediate portions of the end walls and overlying the hone 11 are duplicate companion arms 12 which extend inwardly toward each other in alinement and terminate in laterally directed extremities 13 carrying a fulcrum or pivot bolt 14.

60 The holding and actuating device for the safety razor blade 15 is designated as a unit by the numeral 16 and this comprises a lever which includes a stem 17 having a vertically elongated slot 18 with the slotted portion arranged between the 65 extremities 13 and the bolt 14 extending therethrough to provide the requisite pivotal connection. It will be observed that the pin and slot arrangement permits the lever to be raised up 70 carrying a fulcrum or pivot bolt 14.

75 The holding and actuating device for the safety razor blade 15 is designated as a unit by the numeral 16 and this comprises a lever which includes a stem 17 having a vertically elongated slot 18 with the slotted portion arranged between the 75 extremities 13 and the bolt 14 extending therethrough to provide the requisite pivotal connection. It will be observed that the pin and slot arrangement permits the lever to be raised up 80 carrying a fulcrum or pivot bolt 14.

85 The holding and actuating device for the safety razor blade 15 is designated as a unit by the numeral 16 and this comprises a lever which includes a stem 17 having a vertically elongated slot 18 with the slotted portion arranged between the 85 extremities 13 and the bolt 14 extending therethrough to provide the requisite pivotal connection. It will be observed that the pin and slot arrangement permits the lever to be raised up 90 carrying a fulcrum or pivot bolt 14.

95 In practice, the blade is placed in position as depicted in Figures 2, 4, and 5. The anti-slipping rubber pad 21 is engaged with the blade, the adjustment being made through the medium of the pin and slot connection of the actuating device 16 with said blade. Obviously, the blade is sharpened by moving the lever back and forth in a pendulous manner until the blade is sharp on one face, then the blade is turned over with the fingers and the process is continued until the opposite face is sharp. A little warm water in the hone, which actually functions as a receptacle, will lessen the pressure and expedite the sharpening process.

100 The sharpener will sharpen any two-edged blade now on the market, so far as I know. It will do its work quickly and efficiently. It is unnecessary to depend on the movements of the hand as the lever has a definite mechanical pendulous action which is positive in securing its results. The blade is touched only with the fingers while being placed in position, turned, or removed.

110 The gist of the invention is in the provision of

an abrasive base, preferably of all glass formation, wherein said base is characterized by a convexed honing surface. This surface is described as the hone 11 and is preferably of semi-cylindrical form although this cross sectional shape is not absolutely essential. By forming the hone integral with the end walls and constructing the end walls for effective seating on the table, a firm support for the hone is provided. The essential 10 feature, however, is the pendulous lever which has vertical adjustment and which has a definite movement back and forth in an arcuate path, said lever being provided with means to bear firmly and uniformly on the blade in order to 15 insure even pressure and effective and expeditious results.

It is thought that persons skilled in the art to which the invention relates will be able to obtain a clear understanding of the invention after 20 considering the description in connection with the drawings; therefore, a more lengthy description is regarded as unnecessary.

Minor changes in shape, size, and rearrangement of details coming within the field of invention claimed may be resorted to in actual practice, if desired.

1. A safety razor blade sharpening device, comprising a base having a substantially semi-circular honing surface, a pair of aligned arms connected to the base and extending longitudinally over the said surface, each arm having a right angular extension at its free end, said extensions being spaced apart, a stem passing through said space and having a slot therein, a pin passing through the extensions and through the slot, a head on the lower end of the stem engaging a 80 blade and a handle on the upper end of the stem.

2. A safety razor blade sharpening device comprising a base having a substantially semi-circular honing surface, a stationary pin, means for supporting the pin from the base, said pin extending longitudinally over the said surface, a stem having a longitudinally extending slot therein through which the pin passes for permitting 90 rocking and longitudinal movement of the stem, 95 said supporting means including means for preventing lateral sliding movement of the stem on the pin, a head on the lower end of the stem, and a pad on the lower face of the head for engaging a blade resting on said honing surface. 100

CHARLES EUGENE HOLTZCLAW.
